HANDLE FOR PERCOLATORS AND OTHER UTENSILS

Richard F. Krause, Massillon, Ohio, assignor to The Enterprise Aluminum Company, Massillon, Ohio, a corporation of Ohio

Filed Oct. 7, 1960, Ser. No. 62,417

Term of patent 7 years

(Cl. D44—29)

Fig. 4

Fig. 3

Fig. 1

Fig. 2

Figure 1 is a side elevational view of a handle for percolators and other utensils showing my new design; Figure 2 is a right edge elevational view thereof; Figure 3 is a left edge elevational view thereof; and Figure 4 is a top plan view thereof.

I claim:

The ornamental design for handle for percolators and other utensils, substantially as shown.
